UNITED STATES PATENT OFFICE.

BENJAMIN F. MARTIEN, OF ASHLAND, OHIO.

DESIGN FOR A CHAFFER OR SIEVE SLAT.

SPECIFICATION forming part of Design No. 33,103, dated August 21, 1900.

Application filed July 18, 1900. Serial No. 24,113. Term of patent 14 years.

To all whom it may concern:

Be it known that I, BENJAMIN F. MARTIEN, a citizen of the United States, residing at Ashland, in the county of Ashland and State of Ohio, have invented and produced a new and original Design for a Chaffer or Sieve Slat, of which the following is a specification, reference being had to the accompanying drawings, forming part thereof.

10 Figure 1 is a perspective view of a chaffer or sieve slat, showing my new design. Fig. 2 is an end view of Fig. 1 in elevation.

As shown by the drawings, the leading or characteristic feature of my design consists 15 of a body portion having angular corrugations and a straight bar or rod lying in contact with and intersecting the angular ribs on one side.

20 A represents the parallel ribs on one side of the slat and B the parallel ribs on the opposite side. Between the ribs A are the grooves C, and between the ribs B are the grooves D.

The ribs A have the plain surfaces E, and the grooves C have raised portions F near one end. The straight bar or rod G lies in 25 contact with and intersects the surfaces of the ribs B at one side of the center of the body portion and projects at the ends. The general shape and configuration of the slat is clearly indicated by the drawings and to the 30 eye presents the appearance of a series of alternate projecting corrugations disposed in parallel planes and with a straight bar or rod intersecting the ribs on one side of the body portion.

35 Having described my invention, what I claim as new, and desire to secure by Letters Patent, is—

The design for a chaffer or sieve slat, as herein shown and described.

BENJAMIN F. MARTIEN.
